CLAIM

The ornamental design for an extension slide for a table or similar article, as shown and described.

DESCRIPTION

FIG. 1 is a top plan view of an extension slide for a table or similar article showing my design;

FIG. 2 is a side elevational view;

FIG. 3 is an end elevational view; and

FIG. 4 is a perspective view thereof.

The side of the extension slide not shown is a mirror image of the side shown in FIG. 2.

FIG. 1

FIG. 2

FIG. 3

FIG. 4
